UNITED STATES PATENT OFFICE.

HERMAN A. POPPENHUSEN, OF HAMMOND, INDIANA, ASSIGNOR TO GREEN ENGINEERING COMPANY, OF EAST CHICAGO, INDIANA, A CORPORATION OF ILLINOIS.

FURNACE CONSTRUCTION.

1,243,869.

Specification of Letters Patent. Patented Oct. 23, 1917.

Application filed December 6, 1916. Serial No. 135,466.

To all whom it may concern:

Be it known that I, HERMAN A. POPPENHUSEN, a citizen of the United States, residing at Hammond, in the county of Lake 5 and State of Indiana, have invented new and useful Improvements in Furnace Constructions, of which the following is a specification.

This invention relates to improvements 10 in furnaces, and more particularly to devices for controlling and regulating the draft supplied to furnaces of the type ordinarily used in connection with steam boilers.

Among the objects of the invention is to 15 provide a construction for furnaces wherein both a natural or forced draft may be employed to supply an adequate amount of air to the fuel bed, together with devices adapted to be operated to cut off the natural draft 20 and permit the furnace to operate under forced draft, and likewise to cut off the forced draft and permit the furnace to run under natural draft.

In the operation of commercial boilers 25 and furnaces, it is well known that the load or working condition fluctuates throughout a considerable range, such fluctuations being met by increasing or decreasing the draft, which in turn controls the rate of combustion of the fuel. Under normal conditions a furnace may operate properly under a natural draft, but under conditions of over-load or heavy firing the natural draft would be wholly inadequate, and a forced draft 30 would be required to give the desired results.

The use of forced draft involves the installation of a suitable fan or blower mechanism operated by a motor or other prime 40 mover, hence the exclusive use of a forced draft would not tend to promote efficient operation of the furnace under conditions where natural draft would serve. The provision of means whereby either natural or 45 forced draft can be utilized, and the change from one to the other readily accomplished, serves therefore to increase the efficiency of operation of boilers and to decrease the cost of maintenance of furnaces and their 50 auxiliary operating devices.

The particular type of furnace herein described and embodying the features of the invention is of the so-called "automatic or mechanical stoker" type, embracing the 55 traveling chain form of grate, although, as

will be seen hereinafter, the features of the invention are equally well applicable to all types of furnaces.

The construction of the furnace and the novel features relating thereto are herein- 60 after more fully set forth, the accompanying drawings illustrating a desirable embodiment of the invention, wherein—

Figure 1 is a view in longitudinal section through a furnace containing the features 65 of the invention;

Fig. 2 is a transverse section of the furnace, taken on line 2—2 of Fig. 1;

Fig. 3 is a plan section taken on line 3—3 of Fig. 1, showing the arrangement of ducts 70 and damper operating mechanism; and

Fig. 2^a is a detail view in section, showing the sealing strips on the margins of the dampers.

Referring to the drawings, the parts of 75 the furnace illustrated comprise, in general, the side walls 10, 10, of the brick construction common to furnace settings; a front wall 12; a coking breast 13, extending rearwardly and over the forward end of the 80 fire box or combustion chamber, said front wall and coking breast supporting the front header and forward end of the lower bank of boiler tubes 14. Rearwardly of the front wall 12, and extending upwardly from the 85 floor of the furnace setting, is a bridge wall 15. Within the fire box and extending forwardly from the bridge wall 15 and beyond the front wall 12, is the grate 16, the same having the form of an endless chain, as before mentioned, formed of a multitude of connected together links, the portion of the upper horizontal grate extending rearwardly from the front wall forming the active or fuel bed supporting area of the grate. 90

The chain grate is supported and operated in the following manner: At the sides of the grate and in contact with the inner surface of the side walls 10, 10 are vertical side frame members 17, 17, provided along 100 their upper margins with a plurality of inwardly projecting flanges 18, 18. Spaced apart at suitable intervals along the flanges 18, 18 and preferably integral therewith, are journal bearings 19 supporting the end 105 journals of a plurality of parallel and transversely extending rollers 20, which pass beneath the upper portion of the chain grate and support the same. At the rear ends of the side frame members 17, 17 are mounted 110

plates or extensions 21, 21, which support journal bearings 22. A shaft 23 is journaled in said bearings 22, there being fixed upon said shaft a series of sprocket wheels 24, 24, 5 carrying the chain grate.

From the forward end of the furnace extend vertical side plates 25, 25, in the nature of exterior continuations of the side frame members 17. Journaled in suitable bearings 10 in said plates 25, 25 and extending between the same, is a shaft 26, likewise carrying a series of sprocket wheels 27 meshing with and carrying the forward end of the chain grate. Suitable driving mechanism (not 15 shown) serves to rotate the sprocket shaft, thus moving the chain grate to carry the fuel rearwardly upon the surface of the grate. Immediately above the forward end of the grate 16 is the fuel hopper 28, comprising 20 end walls, integral with the side plates 25, 25, and a downwardly inclined rear wall 29, said hopper communicating at its bottom with the fire box, through an elongated opening intermediate the lower edge of the 25 front wall 12 and the surface of the grate 16, said opening being capable of regulation, as to size, by means of a vertically movable gate 30 and suitable actuating devices (not shown). The fuel is introduced onto 30 the forward end of the grate, and is carried rearwardly on the moving grate until it reaches the rear end, in the form of ash, where it drops by gravity into the ash pit or other receptacle.

35 Referring now to the construction and arrangement of the interior of the furnace, the space below the upper chain or lead of the grate and inwardly from the front wall 12 of the furnace is preferably divided into 40 a plurality of chambers or compartments 31, 32, and 33, formed in the following manner: As shown in Figs. 1 and 3, the side frame members 17 consist of a plurality of sections, of equal length and arranged in 45 pairs, each pair forming the sides of the three compartments. Each section or side frame member is provided at its ends with vertical flanges 34, 34, arranged at right angles and extending inwardly in close 50 proximity to the lateral edges of the grate, there being preferably provided spaces between the flanges, extending the full height of the sections.

Extending transversely of the side frame 55 members 17, 17 are a plurality of transverse frame members 35, the same having the form of I-beam sections, that is, a vertical central web provided with transverse webs 36 and 37 along its upper and lower margins. The transverse frame members 35 are 60 so positioned and of such width as to extend vertically from the supporting rollers 19 downwardly in close proximity to the upper surface of the lower chain or lead of 65 the grate. The ends of the side frame mem-

bers extend into the spaces between the flanges 34 of the side frame members (the end portions of the webs 36 and 37 being removed through the portions between said flanges), and are secured to the side frame 70 members by means of bolts 38 extending through the flanges 34. Extending between the transverse frame members 35 and spaced below the upper lead of the grate 16, are a plurality of partition walls 40, the same consisting of inverted V shaped plates, secured at their ends to the faces of the transverse frame members 35 and sloping or inclined downwardly from the apex, spaced a short 75 distance below the central portion of the 80 grate, the outer margins of said walls terminating just above the side margins of the lower lead of the grate. The partition walls 40 form the bottom walls of the compartments, and, by reason of the inclination 85 thereof, serve to divide each compartment into two passages communicating with one-half of the grate area of each compartment.

Below the lower lead of the grate is provided a plurality of transverse plates 41 extending between the side frame members 17 and in the plane of the transverse frame members 35, the ends of said plates extending into the spaces between the flanges 34 of the side frame members 17 and connected thereto in the same manner as said transverse frame members. The upper margin of each plate 41 is spaced below the under surface of the grate, there being mounted in said space a series of rollers 42, which engage and support the lower portion of the grate, said rollers being provided at their ends with journals, which are mounted within bearings 43, 43, preferably formed integral with the plates 41 and located along 105 the upper margins thereof and immediately below the lateral margins of the grate. The lower margins of the plates 41 are spaced above the floor level or bottom surface of the space below the grate, said margins being 110 preferably arched, as shown in the drawings, thereby forming an opening through each of the partition walls of the compartments, to the end that said compartments communicate with each other at their lower portions 115 and adjacent to the floor of the furnace.

Associated with each compartment are two dampers 44, 44, located at either side of the lower lead of the grate and extending upwardly from the floor of the furnace in 120 the plane of the side margins of the grate and spaced inwardly from the side frame members 17.

The dampers comprise two hinged together plates 45 and 46 extending lengthwise of the compartment, the lower plate 46 being comparatively narrow in width and rotatively supported along its lower margin by a suitable joint, preferably consisting of a downwardly facing groove formed in the 125 130

lower edge of the plate 46 and engaging a rib 47 extending upwardly from the floor of the furnace. The upper plate 45 is connected to the lower plate 46 by means of 5 suitable hinges 48, so arranged as to permit the plates to be flexed in an outward direction. The upper plates 45, 45 extend upwardly a considerable distance above the outer margins of the partition wall 40, and 10 when in the position shown in full lines in the drawings, namely, when the plates 45 and 46 are in vertical alinement, the margins of the partition wall 40 are in contact with the damper and below the upper margins 15 thereof. The dampers associated with each compartment are adapted to be operated by suitable operating mechanism and in a manner to shut off the natural draft and open the forced draft ducts, and vice versa, 20 as will hereinafter be more fully pointed out. In the full line position, shown in Fig. 2, the dampers are in vertical position, and form the inner side wall of a series of pairs of vertical passages 49, 50, and 51 associated 25 with each of the compartments 31, 32, and 33, respectively, and including the spaces between the dampers 44, the side frame members, and the flanges 34, 34 of each side frame member. The vertical passages 30 thus formed extend from the floor of the furnace and communicate at their upper ends with their respective compartments, and, furthermore, are closed from communication with the space below the grate, 35 which is the source of natural draft or free air, inasmuch as the space is open throughout the length of the grate and open to the atmosphere through the lower front portion of the furnace, which is entirely open. 40 Before describing further the mode of operation of the dampers and the means for so doing, the construction employed for supplying the forced draft, or air under pressure, to the furnace will be described. Below 45 the floor level of the furnace is provided a space extending throughout the length and width of the grate and forwardly a short distance beyond the front wall of the furnace, said space being preferably separated 50 from the space immediately below the grate by means of a floor plate 52 of metal or other suitable construction, which terminates inwardly from the side frame members 17 and adjacent to the lower margins of the dampers 44, thereby forming a plurality of floor 55 openings 53 connecting the sub-floor space with each of the vertical passages 49, 50, and 51. The space below the floor plate is divided into a series of longitudinally extending 60 ducts or air passages, formed by means of vertical partition walls 54 extending between the bottom surface of the space and the floor plate. The partition walls are arranged so as to form pairs of ducts adapted 65 to supply air to each compartment through

the vertical side passages thereof, and in the following manner.

The outer pairs of ducts 55, 55 extend only throughout the length of the first or outermost compartment 31, the inner end thereof 70 being closed by providing the partition wall thereof with curved end portions, which terminate at right angles to the longitudinal portions of the walls and in abutting relation with the side wall of the space below 75 the floor. The ducts 55, 55 communicate with the lower ends of the vertical passages 49, 49 associated with the compartment 31 through the openings 53, 53 at the lower ends of the vertical passages. 80

In like manner the pair of ducts 56, 56, located adjacent the outer pair of ducts 55, 55, communicate with the vertical passages of the middle compartment 32, the partition walls 54, 54 thereof extending rearwardly 85 and terminating in curved end portions, which close the end of the duct, as before described. The ducts 56, 56 communicate with the lower ends of the vertical passages 50, 50 through the openings 53 at the lower 90 ends thereof. The central or larger duct 57, formed between the inner walls 54, 54, communicates with the remaining portion of the space located below the rearmost compartment 33, said space in turn communicat- 95 ing with the vertical passages 51, 51 of said compartment 33 in the same manner as do the ducts 55 and 56, heretofore described, namely, by openings similar to 53 at the lower ends of said vertical passages. 100

The outer or forward ends of the ducts 55, 56, and 57 communicate with a space or cross passage 58, common to all, extending transversely of said ducts and adapted to supply air to all of said ducts from a single source 105 of supply, preferably a single passage 59, in which is mounted a fan or blower 60, operated by a motor 61, both fan and motor being preferably mounted in the passage 59, which receives a supply of air through a 110 suitable opening covered with a grating 62 set in the floor in front of the furnace.

From the foregoing description, it is apparent that, with the dampers in vertical or closed position, the air can be supplied to the 115 furnace only through the ducts below the floor, inasmuch as the dampers effectively shut off the air space below the grate. If it is desired to shut off the forced draft and operate the furnace by natural draft, this is 120 accomplished by actuating the dampers by mechanism hereinafter to be described and in a manner to swing them outwardly toward the side frame members, as shown in dotted lines in Fig. 2, namely, with the upper plate 45 extending vertically and lying flat against the surface of the side frame member, and the lower plate inclined outwardly and upwardly over the openings 53, 53. In this position it is seen that the damp- 125

ers completely close the openings 53, thus shutting off the forced draft duct and simultaneously opening the vertical passages to communication with the space below the 5 grate, and thus permitting the free air to pass upwardly through the vertical passages and into the compartments beneath the upper lead of the grate.

Referring now (Fig. 3) to the means for 10 operating the several pairs of dampers 44, 44, it is preferred to employ actuating mechanism capable of operating each pair of dampers associated with the several compartments, independently of each other. 15 Referring first to members of the damper operating mechanism, common to all of the dampers, there is pivotally connected to each damper, adjacent to the lower margins of the upper plates 45 and intermediate their 20 lateral edges, links 65, preferably joined to the journal bearing members 66 fixed to the plates. The links extend inwardly in a horizontal direction and are pivotally connected at their inner ends to links 67, 67 extending 25 transversely of the links 65, said links 67, 67 being pivotally mounted upon the transverse plates 41 by means of bearing members 68, 68, fixed to said plates 41 and having connection with the ends of the links 30 65 by means of downwardly depending connecting members 69, 69.

The links 67, 67 are, in turn, connected to each other and with an operating rod, presently to be described, by means of a transverse bar 70 and short intermediate links 71, 35 71, pivotally connected at their ends with the ends of the bar 70 and the links 67, 67 intermediate the ends of the latter.

As a means for operating the several bars 40 70 independently, and at the same time provide a compact construction, a plurality of endwise movable operating rods 72, 73, and 74 are used, all but one of said rods being tubular, thus permitting the same to be 45 closed or telescoped one within the other. The rods extend longitudinally and centrally of the furnace, below the grate, and are mounted in bearings 75, preferably secured in apertures formed in the several 50 plates 41 below the grate, and forming, as before indicated, a portion of the vertical partition walls of the several compartments.

Considering the rods more in detail, the 55 rod 72 operates the dampers of the forward compartment 31 and consists of a tubular member or sleeve extending inwardly from the front of the furnace a short distance rearwardly of the first compartment and supported in the bearings 75, 75 of the first 60 and second plates 47. Inclosed within the rod 72 is the rod or sleeve 73, which operates the damper of the compartment 32, said rod being tubular but of less diameter than the outer rod 72 and of greater length, 65 extending beyond the inner end of said rod

72 a short distance beyond the plate 47 intermediate the compartments 32 and 33 and supported in the bearing 75 of said plate.

In the same manner, the rod 74 is mounted 70 within the tubular rod 73 and extends rearwardly to the rearmost plate 47 and mounted in the bearing 75 thereof, said rod 74 being of less diameter and of greater length than the rods 72 and 73 and preferably solid rather than tubular as are the rods 72 and 73. The rods 72, 73, and 74 operate the dampers of the compartments 31, 32, and 33 respectively, as before suggested, each rod being connected to its 80 respective bar 70, which is provided with a centrally located collar surrounding the rod. The several rods are operated from the forward end of the furnace by a series of levers arranged in the following manner: 85 Extending transversely of the forwardly extending frame members 25, 25, is a shaft 76, rotatively mounted in bearings provided in said frame members, said shaft projecting beyond the frame members on one side 90 of the furnace. Intermediate the ends of the said shaft is provided a fixed crank arm 77, having connection with the end of said rod 74 by means of a link 78, said rod projecting forwardly a short distance beyond 95 the end of the tubular rod 73. At the outer end of the shaft 76 is a lever 79, adapted to be operated by hand to rotate the shaft 76 and, through the crank and link connection, to move the rod 74 endwise, the endwise 100 movement of the rod transmitting the desired swinging movement to the dampers through the intermediate arrangement of the bars 70 and links 71, 67, and 65.

Mounted upon the shaft 76 is a rotative tube 80, extending from the central portion of said shaft through one of the side frame members, and terminating adjacent the lever 79, said tube being provided at its outer end with a lever 81 and at its inner end with a crank arm 82 connected to the adjacent end of the rod 73 by means of a link 83, said rod extending a short distance beyond the end of the surrounding rod 72. In like manner the tube 80 is surrounded 115 by a larger tube 84, rotatively mounted thereon and extending through the side plate and provided at its outer end with a lever 85 and at its inner end with a crank arm 86 connected to the rod 72 by means of a link 87. By rotating the tubular shafts 80 and 84 by means of their respective levers 81 and 85, the rods 73 and 72, respectively, are moved endwise and operate the pair of dampers connected thereto, in the same 120 manner as hereinbefore described in connection with the shaft 76.

Inasmuch as it is desirable to make each compartment quite independent, so far as possible, from the other compartments, 125

means are employed to confine the draft within the passages of each compartment and to eliminate the leakage of air by the dampers and from one compartment to another. To accomplish this purpose, there are provided along the lateral margins of the dampers strips 88 (Fig. 2^a) of flexible material, of sheet metal or other suitable material, which extend beyond the margins of said dampers and contact with the adjacent surfaces of the transverse flanges 34 of the side wall sections 17, thus closing the clearance spaces which otherwise would permit a considerable amount of air to leak by the dampers. Furthermore, there are provided along the top margin of the partition walls between the compartments, vertical extensions, in the form of angle-bars 89, extending transversely of the grate and mounted on the upper webs 36 of the transverse frame members 35, said angle-bars having a vertically projecting web extending in close proximity to the under surface of the grate. The purpose of this extension is to close the vertical space between the upper edges of the transverse frame members and the grate.

A furnace constructed in accordance with the particular arrangement of air passages and dampers is capable of being controlled and to be accurately regulated to meet all conditions of load, by manipulating the damper controlling levers, so connected to the dampers through the intermediate operating mechanism that not only can the draft be instantly and completely changed from forced to natural, but separate portions of the grate can be supplied with either form of draft, by the provision of independently operated dampers in the several compartments. Thus each compartment divides the entire grate surface into a number of units or sections, each section being capable of regulation as to the draft supplied thereto, quite independently of the other sections.

The novel features of the invention hereinbefore described are more specifically set forth in the appended claims.

I claim as my invention:

50 1. In a furnace, the combination of a grate, an air space beneath the grate communicating with a source of free air and a source of forced draft, and a damper mounted in said free air space intermediate the sources of forced draft and of free air, and movable into position to shut off the supply of free air to said air space and to form a passage connecting said air space with said forced draft duct.

60 2. In a furnace, the combination of a grate, an air space beneath said grate communicating with a source of free air, a forced draft duct opening into said air space, and a damper mounted in said air space intermediate the source of free air and

the opening of said air duct, and movable into one position to form a passage shut off from the source of free air and connecting said air space and forced draft duct, and into another position to close the opening of 70 said forced draft duct and to permit the supply of free air to the grate.

3. In a furnace, the combination of a grate, a compartment below said grate provided with a passage adapted to communicate with sources of natural and forced draft, and a damper mounted in said passage, intermediate said sources of natural and forced draft and movable into one position to close said passage from communication with said source of natural draft and open communication with said source of forced draft, and into another position to close said passage from communication with said source of forced draft and open communication with said source of natural draft.

4. In a furnace, the combination of a grate, a compartment formed beneath said grate, adapted to communicate with a free 90 air space included between opposite walls of the furnace below the compartment, by means of an opening adjacent one of said walls, a damper mounted in said free air space and spaced from said wall and adapted to be 95 moved into and out of position to form a passage shut off from said free air space and communicating with said opening to said compartment, and a forced draft duct, and means for supplying forced draft to said 100 passage.

5. In a furnace, the combination of a grate, a compartment beneath said grate, adapted to communicate with a free air space below said compartment, a forced 105 draft duct communicating with said free air space, and a damper mounted in said free air space adjacent to the furnace wall and movable into one position to form a passage shut off from said free air space and connecting said compartment with said forced draft duct, and into another position to close said forced draft duct.

6. In a furnace, the combination of a grate, a compartment beneath said grate, 115 adapted to communicate with a free air space adjacent said compartment, a damper mounted in said free air space and movable into and out of position to convert a part of said free air space into a passage communicating with said compartment and shut off from said free air space, and a forced draft duct adapted to communicate with said compartment through said passage and to be closed by said damper when moved out of 120 position to form said passage.

7. In a furnace, the combination of a grate, a compartment beneath said grate, provided with an opening communicating with a free air space below said compartment 130

- ment, a forced draft duct communicating with said free air space below the opening to said compartment, and a damper movably mounted in said free air space and adapted
- 5 when in one position to inclose a portion of said free air space to form a vertical passage connecting said forced draft duct with said opening to said compartment, and in another position to close the opening of said
- 10 air duct.
8. In a furnace, the combination of a grate, a compartment below said grate provided with an opening between the margins of the grate and a side wall of the furnace,
- 15 said opening communicating with a free air space below the compartment, a forced draft communicating with said free air space below said opening, and a vertically arranged damper spaced inwardly from said wall and
- 20 adapted in one position to form a passage shut off from the air space and connecting said opening of the compartment with said forced draft duct, and in another position to shut off said forced draft duct and open
- 25 communication between said compartment and said free air space.
9. In a furnace, the combination of side walls, a grate, a compartment formed beneath said grate, said side walls being spaced
- 30 outwardly from the edges of said grate and forming openings connecting said compartment with a free air space therebelow, forced draft ducts communicating with said free air space adjacent said side walls, and a
- 35 damper mounted in said free air space in spaced relation to said walls and movable into one position to form vertical passages communicating with said compartment and with said forced draft ducts, and into an-
- 40 other position to merge said passage into the free air space and to shut off said forced draft ducts.
10. In a furnace, the combination of a grate, the side walls of the furnace below
- 45 the grate being spaced outwardly from the adjacent margin of the grate, a partition wall intermediate the grate and floor of the furnace and terminating short of the side walls and forming an air space adapted to
- 50 have communication with the atmosphere through an opening adjacent a side wall, a vertically arranged partition wall spaced inwardly from a side frame member and forming an air passage therebetween, and an air
- 55 duct communicating with said air passage, said partition wall being movable toward the side wall of the furnace, to permit free air to enter the compartment and to close said air duct.
- 60 11. In a furnace, the combination of a grate, vertical side frame members, supporting said grate and spaced outwardly therefrom to provide vertical passages on either side of the grate, a partition wall spaced
- 65 below said grate and forming with said side frame members an air compartment having communication with the atmosphere through said vertical passages, a damper spaced inwardly from the side frame members and forming a wall of said passages, and an air
- 70 duct communicating with the lower end of each of said vertical passages, said damper being operable to shut off communication between said compartment and either the atmosphere or said air duct.
- 75
12. In a furnace, the combination of a grate, a horizontal partition wall intermediate the grate and floor of the furnace and forming a compartment, said partition wall terminating short of a side wall of the furnace and providing an opening communicating with a free air space below said partition wall, an air duct for conducting air under pressure to said free air space and communicating therewith adjacent the side
- 80 walls of the furnace, and a vertical partition wall extending downwardly from the edge of said horizontal partition wall and spaced inwardly from the side wall of the furnace and beyond the opening of said air duct, and
- 85 movable into one position to form an air passage closed from communication with said air space, and into another position to close said air duct.
- 90
13. In a furnace, the combination of a
- 95 grate, a partition wall intermediate the grate and the floor of the furnace and forming an air compartment beneath the grate, there being provided openings in said compartment adjacent the side walls, communicating with
- 100 a free air space below said compartment, an air duct for conducting air under pressure to said air space and opening thereinto adjacent a side wall of the furnace, a damper comprising hinged together plates pivotally
- 105 mounted upon the floor of the furnace and spaced inwardly from the side wall and adjacent the opening of said air duct, said damper plates when in vertical position forming a passage closed from communication with said free air space, and when moved toward the side wall of the furnace to close the opening of the air duct, and
- 110 means for operating said damper.
14. In a furnace, the combination of a
- 115 grate, a compartment beneath said grate and communicating with a free air space below the compartment, an air duct for conducting air under pressure to said free air space and communicating therewith through an
- 120 opening in the floor of the furnace below the opening to said compartment, and a damper comprising hinged together plates, the lower plate being pivotally mounted upon the floor of the furnace adjacent the
- 125 air duct opening, said damper plates when in vertical position serving to inclose a portion of the free air space to form a passage between said compartment and air duct, and when moved into another position to open
- 130

communication between the compartment and free air space, the lower plate of the damper acting as a closure for the opening of the air duct.

- 5 15. In a furnace, the combination of a grate mounted in the combustion chamber of the furnace, a series of separate compartments below said grate and adapted to have communication with the atmosphere, a series of separate air ducts for supplying air to said compartments, a damper associated with each compartment to control the supply of free-air or air under pressure to said compartment, a plurality of operating rods 10 15 in telescoped arrangement, each operatively connected to one of said dampers, and levers mounted exterior of the furnace and connected to said operating rods, to actuate said dampers independently of each other.
- 20 16. In a furnace, the combination of a traveling grate, a series of compartments

formed between the upper and lower portions of said grate, said compartments having communication with a common free air space below the grate, a series of air ducts 25 communicating with the free air space, adapted to supply air under pressure to said compartments, a series of dampers mounted in said air space and adapted in one position to form a passage connecting each compartment with its corresponding air duct, and in another position to close said air ducts, and independent operating means connected with each of said dampers.

In testimony that I claim the foregoing 35 as my invention I affix my signature in the presence of two witnesses, this 2nd day of December, A. D. 1916.

HERMAN A. POPPENHUSEN.
